[57] CLAIM

The ornamental design for a suspendable bag, as shown and described.

DESCRIPTION

FIG. 1 is a perspective view of a suspendable bag showing my new design;

FIG. 2 is a front elevational view;

FIG. 3 is a view looking from the right of FIG. 2, the opposite side being the same in appearance;

FIG. 4 is a top plan view;

FIG. 5 is a rear elevational view; and

FIG. 6 is a bottom plan view.

FIG. 4

FIG. 5

FIG. 6
